UNITED STATES PATENT OFFICE.

ARNOLD F. MOLLRING, OF NEBRASKA CITY, NEBRASKA.

IMPROVEMENT IN MACHINES FOR MAKING MEASURE-SLIPS.

Specification forming part of Letters Patent No. 222,932, dated December 23, 1879; application filed September 29, 1879.

To all whom it may concern:

Be it known that I, ARNOLD F. MOLLRING, of Nebraska City, in the county of Otoe and State of Nebraska, have invented a new and valuable Improvement in Machines for Making Measure-Slips for Dry-Goods; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a longitudinal vertical section of my invention. Fig. 2 is a top view of the type-wheel, and Figs. 3 and 4 are details.

This invention has relation to improvements in machines for printing and cutting measuring-strips designed to be rolled up with the goods for the purpose of conveniently measuring the same, and indicating, without the use of the yard-stick, any desired length in selling the same.

The nature of the invention will be fully set forth hereinafter.

In the annexed drawings, the letter A designates a strong frame having near one end the uprights *a*, in the upper ends of which is journaled the type-wheel B. This wheel may be of any desired diameter, according to the length of the strips sought to be printed, and of a width, say, of two feet, which will allow twenty-four strips one inch wide to be printed at a time. This wheel, if designed to print strips twenty-five yards in length, is provided at its perimeter with an equal number of rectangular strips, *i*, in which will be set type in rows one inch apart, and in regular order from one to twenty-five. Intermediate to the type-holding strips *i* are other strips, *i'*, tapering to an edge from end to end, and having their edges equidistant from the axis of the wheel with the printing-surface of the type. These strips *i'* print across the measuring-strips the half-yard mark. As the wheel revolves, the type and the edges of the half-yard strips *i'* come in contact with an ink-roller, C, to and upon which the ink is spread evenly by a distributing-roller, D. The rollers C D are held in yielding contact with the type-wheel by suitable springs *b*.

E indicates a storing-roller, upon which the

material to be printed is wound. This roller is arranged at the lower part of the frame, nearly directly under the type-wheel, and the paper passes from it in front of and around a tension-roller, F, arranged above and somewhat in front of the storing-roller aforesaid. It passes thence upward and backward over and around a roller, G, which may be denominated the "plateau," and which is so situated with regard to the type-wheel that the types and the half-yard strips bear upon the paper as it passes over the roller G. After passing over this roller the paper passes to the front downward under a tension-roller, H, and is secured to a winding-roller, I, at the front end of the frame.

Intermediate to the rollers H and I is a mandrel, J, on, or about on, a level with roller H, upon which are secured at intervals of an inch a gang of circular cutters, K, the cutting-edges of which are above the highest point of tension-roller H aforesaid and the lowest point of the winding-roller I. This roller has upon the end of one of its journals a master-gear, L, that engages a pinion, *c*, upon the end of the cutter-mandrel J, and imparts motion thereto in an opposite direction. Upon the adjacent ends of the measuring platen-roller and ink-roller, respectively, are the pulleys *d* *d'*, connected by an endless belt, *e*.

It will be seen that all the rollers derive motion through the medium of the paper band P, which, owing to the tension-rollers, acts as a transmitter from the winding-roller I.

The measuring-roller G is provided at one end with a projecting tappet, *f*, that at each complete rotation of the said roller comes in contact with metallic cogs *o*, projecting radially from the adjacent edge of the type-wheel, and imparts an intermittently-rotating movement thereto. These cogs are arranged at the end of the type and half-yard strips *i* and *i'* aforesaid. At each complete revolution of the measuring-roller a half-yard of the paper band is measured off, and that length marked off on the same, the said roller being one-half yard in circumference.

It will be seen that the entire apparatus derives motion through the paper band from the winding-roller, and that as the said band tightens the cutting-knives will divide it into strips.

N is a lever pivoted to the upright, and de-

signed to raise the type-wheel slightly at one end, so that it may be turned backward or forward to any desired starting-point.

The type-wheel may, if desired, be held against backward rotation by means of a spring, a pawl-and-ratchet device, or other means.

What I claim as new, and desire to secure by Letters Patent, is—

1. In a machine for cutting and printing measuring-slips for roll-goods, the combination, with the type-wheel B, having the alternately-arranged type-carrying strips *i* and the beveled strips *i'*, of the platen-roller G, as and for the purpose specified.

2. The combination, with a platen measure-roll, G, an inking-roller, C, a storing-reel, E, tension-rolls F H, a winding-reel, I, and a mandrel, J, carrying the spaced cutters, of the in-

termittently-rotating wheel B, carrying on its perimeter the type-holding strips *i* and the beveled sharp-edged strips *i'*, alternately arranged, substantially as specified.

3. The combination of the type-wheel B, measuring-roller G, inking-roller C, storing-roller E, carrying the paper band P, the tension-rollers F H, and the winding-reel I, and the mandrel J, carrying the cutters K, substantially as specified.

In testimony that I claim the above I have hereunto subscribed my name in the presence of two witnesses.

ARNOLD FREDRICK MOLLRING.
